UNITED STATES PATENT OFFICE.

CHESTER N. JOHNSON, OF CHICAGO, ILLINOIS.

INSULATING DEVICE.

1,288,016.

Specification of Letters Patent. Patented Dec. 17, 1918.

Application filed May 29, 1913. Serial No. 770,577.

To all whom it may concern:

Be it known that I, CHESTER N. JOHNSON, a citizen of the United States, residing at Chicago, in the county of Cook and State of Illinois, have invented certain new and useful Improvements in Insulating Devices, of which the following is a specification.

This invention relates to improvements in insulating devices. Hitherto in wiring buildings or in leading wires through conduits it has been the practice to branch the leads or terminals through more or less complicated and clumsy insulating devices, such as branch boxes, junction boxes, etc. The object of my invention is to provide an improved device which will enable wires to be separated when led from a pipe or other conduit and at the same time providing an insulation for such wires. Frequently where leads are taken through the end of a pipe contact with the pipe at its end will result in the fraying or breaking down of the wire insulation, causing a short circuit and often times resulting in fire. To obviate these dangers I provide a simple form of device adapted to be secured at the end of a pipe or conduit to prevent fraying of the wire insulation, and also, as stated above, to provide a spreading device which will separate the different leads and insulate them at the same time. Another object is to provide an improved form of wire insulator and spreader which will enable the branching of individual leads and which may be easily secured to the end of a pipe without requiring rotation of the spreading and insulating member, so that where the same is of an elongated form it may rest against a wall or floor and may be secured in such position without twisting of the wires or spreader. Other objects will be made apparent as set forth in the following specification and accompanying drawings, in which—

Figure 1 is a vertical section through a pipe or conduit showing my invention applied thereto.

Fig. 2 is a section along the line 2, 2 of Fig. 1.

Fig. 3 is a perspective of a slight modification.

Fig. 4 is a sectional view of the modified form shown in Fig. 3.

Like numerals refer to like elements throughout the drawings, in which 10 designates a pipe or conduit externally threaded at its extremity 10^a. Extending through

this conduit is shown a double wiring lead 11 containing the two individual leads 11^a and 11^b suitably insulated as shown in Fig. 1. To protect and separate the individual leads I provide a spreading member generally indicated by numeral 12, shown in Figs. 1 and 2, provided with a main passage 12^a and branch passages 12^b, 12^c leading outwardly therefrom. This spreader 12 is integrally formed of suitable insulating material, such as porcelain, and is adapted to be constructed in sizes corresponding to the size of pipe or conduit 10 used therewith so that the end of passage 12^a will aline with and be of substantially the same diameter as the inner diameter of the pipe 10.

To suitably secure the spreader 12 to the pipe I provide a coupling member or sleeve 13 comprising the internally threaded portion 13^a and the enlarged bore 13^b of an inner diameter slightly larger than the exterior diameter of the base flange 12^d of the spreader 12. The spreader 12 is formed above the flange 12^d with the reduced neck 12^e forming the exterior groove 12^f.

When the device is assembled the outer extremity 13^c of the coupling member 13 is spun or swaged inwardly to fit around the reduced neck 12^e of spreader 12, the same being held thereby and prevented from separation therefrom by the inner shoulder 13^a and inturned end 13^c. This construction permits the sleeve 13 to be rotated relative to the spreader 12, but prevents separation of the two members.

In utilizing the device the leads 11^a, 11^b are drawn through the respective passages 12^b, 12^c and the spreader 12 is drawn into close contact with the end of the pipe 10 by means of the threaded sleeve 13, the latter being provided with the hexagonal outer periphery 13^e adapted to be engaged by a wrench. Since the sleeve 13 may be rotated relative to the spreader 12, the twisting of the wires 11^a, 11^b is obviated and the spreader 12 may be easily drawn into close contact with the extremity of the pipe 10 as stated above, thereby protecting the insulation of the wires from rubbing against the sharp edges of the pipe end.

Variations in the number of passages for the individual leads may be made according to conditions met with in practice. In Figs. 3 and 4 I have shown a spreader 12' having three separate passages and being formed of slightly elongated shape to pro-

vide for the extra passage. In other respects the construction is the same.

It will be apparent where it is necessary to separate the leads for ease of connections, 5 etc., and where the pipe is located adjacent the floor or wall, it would be inconvenient to have to rotate the spreader 12 owing to the lack of space afforded. Furthermore, such 10 rotational movement would result in the twisting of the wires. I eliminate these objections by providing the rotatable coupling sleeve which may be rotated relative to the spreader 12 and which will at the same time 15 serve to draw the spreader into contact with the pipe 10, and will secure the same in such position.

While I have shown and described my improved device with more or less particularity, I do not wish to be unduly restricted 20 thereto beyond the scope of the appended claims.

What I claim is:

1. An insulating cap for closing the outlet 25 end of a conduit in which electric wires are placed and for permitting said wires to pass therethrough, the lower end of said cap engaging the end of said conduit and being arranged in alinement therewith, said cap including openings extending therethrough 30 and arranged at an angle to the axis of the cap, said openings terminating at the said lower end of the cap and in immediate prox-

imity to the end of said conduit, the walls of said openings being flush with the inner wall of said conduit whereby a smooth and 35 uninterrupted passage is provided for said wires, a protecting band surrounding and rotatably supporting said cap by engagement with the lower side and end portion thereof, and means operated by the rotation 40 of said band for attaching the same to the conduit.

2. An insulating cap for closing the outlet end of a conduit in which electric wires are placed, and for permitting said wires to 45 pass therethrough, said cap including openings extending therethrough and arranged at an angle to the axis of the cap, said cap being further provided with a groove extending around the same, a protecting band 50 surrounding the lower side and end portion of the cap and having parts loosely engaging said groove whereby said band and said cap are relatively rotatable, and means for attaching the band to the conduit in such wise 55 that said cap is suspended entirely below the end of said conduit.

In testimony whereof I have subscribed my name.

CHESTER N. JOHNSON.
